ROLLER SHADE

Herman H. Koller and Wilfred G. Dery
Amsterdam, N. Y.

Application February 20, 1935, Serial No. 7,425

1. Claim. (Cl. 156—17)

This invention relates to improvements in roller shades, the general object of the invention being to improve the devices shown in a patent granted to us on October 16, 1934, No. 1,976,884 and Patent No. 1,917,449 dated July 11, 1933 granted to Herman H. Koller.

This invention also consists in certain other features of construction and in the combination and arrangement of several parts, to be herein-after fully described, illustrated in the accompanying drawings and specifically pointed out in the appended claim.

In describing the invention in detail, reference will be had to the accompanying drawings wherein like characters denote like or corresponding parts throughout the several views, and in which:

Fig. 1 is a fragmentary front view of the invention with parts broken away.

Fig. 2 is a vertical sectional view through Fig. 1.

Fig. 3 is a fragmentary elevation showing how the spring for holding a slat in raised position, is arranged.

Fig. 4 is a fragmentary perspective view showing how the chain engages a channel guide.

Fig. 5 is a perspective view of one of the slats.

Fig. 6 is a transverse sectional view through the upper rolled end of a slat, and the channel guide and the chain with the rod in elevation.

In these drawings, the numeral 1 indicates a pair of vertically arranged channel members suitably placed in the side members of a window frame or the like and the numeral 2 indicates a pair of supporting plates which may contact or be formed with the upper ends of the bights of the members 1 and these plates may also be supported

in the upper portion of a window frame against the side members thereof. These plates rotatably support a shaft 3 which has a drum 4 attached to each end part thereof, and a chain

5 is connected to each drum, the chain operating in the guide members 1 as more clearly shown in Fig. 4. These chains have the vertically spaced rods 6 attached to certain links thereof and each rod supports a slat 7 which may have its upper edge rolled as shown at 8 around the rod.

Each slat is of slightly arcuate shape with its concave face uppermost, when the slats are in open position so that the slats can readily be rolled upon the drums with the chains. The second shaft 9 is rotatably supported by the plates 2 in front and slightly below the shaft 3 and these two shafts are connected together adjacent one end by the gears 10. A strap 11 has one end connected with the shaft 9 and its other end is connected to a spring roller 12 at the lower end of one side of the frame so that when the strap 11 is pulled upon in a downward direction, it will

rotate the shaft 9 and the strap will be rolled upon the shaft 12 and this moving of the shaft 9 will be communicated by the gears to the shaft 3 and as the shaft 3 rotates in an opposite direction from the shaft 9, the slats and chains will be rolled upon the drums 4. A spring 13 is connected with the upper slat and tends to hold the same in open position and if desired springs similar to 13 can be associated with the other slats.

A frame 15 composed of a pair of vertical bars 10 and a lower cross piece 16 is supported for swinging movement from the members 1 by the links 17 the bars engaging the free edges of the slats and said frame is actuated by an arcuate-shaped lever 18 having its inner end pivoted to the cross piece 15 16, part of the lever passing through a hole in the stationary lower slat 1' and through a guide 19 on the window sill, the edges of the lever 18 being notched so that the guide will hold the lever in adjusted position and the slots or notches 20 in the member 1' will fit over the lever when the blind is in lowered position. Thus by pulling outwardly the lever 18, the frame 15 will be lowered and as part of the frame bears against the slats, this movement of the frame will lower 25 the slats to closed or partly closed position.

It is thought from the foregoing description that the advantages and novel features of the invention will be readily apparent.

It is to be understood that changes may be 30 made in the construction and in the combination and arrangement of the several parts provided that such changes fall within the scope of the appended claim.

We claim:

In a shade structure of the class described, a transversely arranged shaft rotatably supported, drums on the shaft adjacent the ends thereof, a chain having one end connected to each drum, arcuate-shaped slats, a rod connected to one edge 40 of each slat, the ends of the rods being connected to spaced links of the chains, guideways for the chains, a second shaft rotatably supported, gears connecting the two shafts together, and a strap connected to the second shaft and so wound on 45 the second shaft that a pull upon the strap will cause the gears to rotate the first shaft in an opposite direction from the second shaft to wind the chains and slats upon the drums, a frame having portions contacting the free edges of the 50 slats, means for supporting the frame for swinging movement, and a manually-operated lever connected to the lower end of the frame for swinging the frame and holding it in adjusted position.

HERMAN H. KOLLER.
WILFRED G. DERY.
